UNITED STATES PATENT OFFICE

ERIC N. BERGGREN, OF CHICAGO, ILLINOIS, ASSIGNOR TO WILLIAM ANDERSON, OF CHICAGO, ILLINOIS

DESIGN FOR A SPRAY GUN

Application filed January 10, 1931. Serial No. 38,267. Term of patent 14 years.

To all whom it may concern:

Be it known that I, ERIC N. BERGGREN, a citizen of the United States, residing at Chicago, in the county of Cook and State of Illinois, have invented a new, original, and ornamental Design for Spray Gun, of which the following is a specification, reference being had to the accompanying drawings, forming a part hereof.

In the drawings,

Fig. 1 is a perspective view of a spray gun showing my new design.

Fig. 2 is a top plan view thereof.

I claim:

The ornamental design for a spray gun, as shown.

E. N. BERGGREN.
